UNITED STATES PATENT OFFICE.

WILLIAM L. BLISS, OF NIAGARA FALLS, NEW YORK, ASSIGNOR, BY MESNE ASSIGNMENTS, TO U. S. LIGHT & HEAT CORPORATION, OF NIAGARA FALLS, NEW YORK, A CORPORATION OF NEW YORK.

AUTOMATIC ELECTRIC REGULATOR.

1,197,177.

Specification of Letters Patent.

Patented Sept. 5, 1916.

Application filed April 29, 1911, Serial No. 624,112. Renewed July 28, 1916. Serial No. 111,957.

To all whom it may concern:

Be it known that I, WILLIAM L. BLISS, a citizen of the United States, residing at Niagara Falls, in the county of Niagara and 5 State of New York, have invented new and useful Improvements in Automatic Electric Regulators, of which the following is a full, clear, concise, and exact description, reference being had to the accompanying drawings, forming a part of this specification.

My invention relates to automatic electric regulators.

One of the objects of the invention is to provide a regulator which shall regulate 15 voltage within close limits and which shall be stable in operation.

Another object is to provide a regulator having various improved instrumentalities, each of which may be adjusted so as to produce 20 the desired coöperation with the remaining instrumentalities.

In the accompanying drawings, the preferred form of regulator is illustrated as applied to a car lighting system. The regulator may assume other forms and may be used in other circuits and systems.

Referring to the drawings, Figure 1 illustrates diagrammatically a regulator connected in a car lighting system which includes 30 a regulator; Figs. 2 and 3 illustrate respectively, a front and side elevation of the regulator relay.

The drawings show a generator having an armature 1 and shunt field 2 having in series therewith any suitable regulating resistance 3. The external circuit of the generator is through conductors 4 and 5. An automatic switch 6 is adapted to close the external circuit through a storage battery 7 40 connected across said circuit and through lamps 8 connected in parallel across said circuit. The switch 9 is adapted to open and close the circuit to the lamps.

In order to prevent an excessive voltage 45 from being impressed on the lamps, I provide a variable resistance 10 in series therewith. The variable resistance consists of a series of carbon plates normally under pressure between end blocks, one of which is 50 adjustable and the other of which may be moved by lever 11, bell crank lever 12 and plunger 13 to vary the pressure on said plates. The plunger 13 is normally in lowermost position, due to its weight assisted

by a spring 14 whereby the resistance 10 is 55 normally minimum. A dash pot 15 steadies the action of the plunger and associated parts.

The variations of the resistance 10, due to the movement of the plunger 13, are controlled by the solenoid 16, connected in shunt across the circuit through an adjustable resistance 17. The solenoid 16 is normally short circuited by the contact member 18, held in uppermost position by a spring 19. 65

A voltage responsive coil 20 is connected in shunt across the circuit and upon prearranged rise in voltage, is adapted to move the member 18 downwardly for the purpose of introducing solenoid 16 into the circuit. 70 A differential coil 21 is connected in a parallel branch with solenoid 16. A suitable fuse 21' is connected in the shunt circuit of the three coils 16, 20 and 21. The differential coil is short circuited when said 75 solenoid 16 is short circuited and is energized when said solenoid is energized to oppose or counteract the voltage coil 20 and permit the spring 19 to again retract the short circuiting contact member 18. Thus it 80 compensates for the varying reluctance of the air gap and by increasing the rapidity of the vibrations, the sensitiveness of the regulator is increased. While this action is obtained in the preferred construction by 85 connecting the coil 21 in parallel with the coil 20, I do not limit myself to this connection.

The operation of the variable resistance device is as follows: Upon a tendency of 90 the impressed voltage on the lamp circuit to increase above the proper value, the voltage coil 20 opens the short circuit and introduces the solenoid 16 into the circuit. The plunger 13 is drawn up thereby relieving 95 somewhat the pressure on the carbon plates and increasing the resistance in series with the lamps. The increased resistance tends to cause a decrease in the energization of the voltage coil 20 whereupon the spring 100 19 retracts and the solenoid 16 is again short circuited. The cycle of operation is repeated rapidly, the vibration of the contact member 18 being very rapid. The differential coil 21 increases the rapidity of 105 the vibration by opposing the voltage coil as soon as the short circuit is opened. When there is a tendency to impress a still higher

voltage on the lamp circuit, the solenoid 16 is introduced into the circuit for correspondingly longer successive intervals of time. The current flowing through solenoid 16 during such longer intervals of time is greater, due to the increasing voltage. Hence, both the current and the effective intervals are probably greater, producing a magnifying effect. For this reason the regulator responds readily to any slight tendency toward voltage increase. Thus it will be seen that the character of the vibration determines the regulation.

In practice the variable resistance and associated parts are usually mounted beneath the car. The short circuiting device or regulator relay is usually mounted in the car. Of course, both devices may be mounted on a common panel, if desired.

20 The preferred structure of the regulator relay is shown in Figs. 2 and 3. The base or panel 22 supports the iron-clad magnet frame 23 enveloping the voltage coil and differential coil described above. The core 25 or plunger 24 is supported above and below by resilient vibratile members 25. An arm 26 projects from the lower end of the core and has secured thereto the spring 19 having the function described above. The 30 spring is adjustable by means of the screw 27. The lower end of the core 24 carries the arm 12 provided at opposite ends with contacts 28 adapted to coöperate with stationary contacts 29 for rapidly opening the circuit 35 through the arm 12 when the plunger or core is vibrated. Each stationary contact is resiliently mounted on a helical spring 30 which may be adjusted by the stud 31. Although in the preferred construction two 40 sets of contacts are employed, I do not limit myself to this number.

In view of the various adjustments described, it is apparent that the plunger and contacts may be so regulated as to produce 45 a very rapid short circuiting action. By the use of a double set of contacts the sparking is reduced.

I do not desire to limit myself to the details of construction described above, but 50 desire to cover any suitable means for accomplishing the desired result and falling within the scope of the appended claims.

I claim as my invention—

1. A relay for a lamp regulator comprising a base or panel, a differentially wound solenoid mounted thereon, said solenoid comprising a voltage responsive coil and an opposing coil, a core vertically mounted within said solenoid and supported at opposite ends by resilient vibratile reeds, a

spring adjustably secured near the top of said solenoid at one end and connected to an extension of said core at its other end to partially support said core, a contact arm carried by a lower end of said core and having a carbon contact at each end, a relatively stationary carbon contact coöperating with each of said first contacts and resiliently mounted, means for adjusting said stationary contacts whereby upon energization of said voltage coil said arm and the contacts carried thereby may be rapidly vibrated to periodically open and close a circuit in a branch of which said opposing coil is included.

2. A regulator comprising a variable pressure rheostat, a controlling winding for operating said rheostat and a relay device for normally short-circuiting said controlling winding but adapted to introduce said winding rapidly into circuit for regulating purposes, said relay being responsive to variations in voltage and including a double contact device and a voltage coil for operating said double contacts.

3. A regulator including a variable pressure rheostat, a controlling solenoid for said rheostat, and a vibrating relay device for normally short-circuiting said solenoid but adapted to introduce it into a shunt circuit intermittently for regulating purposes, said relay being responsive to variations in voltage and including a double contact device, a voltage coil for operating said double contacts and a differential coil connected in parallel with said controlling solenoid and normally short-circuited by said contacts.

4. A regulator comprising contacting carbon plates arranged to form part of an electric circuit, a series of levers connected to a movable core for varying the pressure on the series of plates to vary the resistance of the circuit, a controlling winding for operating said core, and a relay device for normally short-circuiting said winding but adapted to introduce it into a shunt circuit at rapid intervals for regulating purposes, said relay being responsive to voltage rise on said circuit and including a double contact device, a voltage coil for operating the contacts, and a differential coil connected in parallel with said winding and normally short-circuited by said contacts.

In witness whereof, I have hereunto subscribed my name in the presence of two witnesses.

WILLIAM L. BLISS.
